WARP STOP MOTION CONTACT BAR AND DROP WIRE

Application filed July 9, 1930. Serial No. 466,705.

This invention is a continuation in part of my copending application Ser. No. 350,401 and is concerned more particularly with certain relations existing between the drop wire and contact bar of an electrical warp stop motion.

The warp stop motion to which my invention relates operates electrically with contact bars, one for each bank of drop wires, and the wires are provided with slots in their upper portions through which the bars pass. Each bar is formed of two electrodes one of which is grounded and acts as a support for the live electrode insulated therefrom. I find it convenient to locate the exposed surface of the live electrode within the outline of the grounded electrode, this construction requiring a lateral motion on the part of the drop wire to establish electrical connection between the electrodes. The lateral motion is brought about by the co-action of a lobe on the drop wire positioned to engage a longitudinally extending camming rib on the grounded electrode. As the drop wire falls the lobe is moved laterally by the rib and the drop wire must be provided with clearance above the lobe to permit the lateral motion.

In drop wires having slots of any appreciable width in their upper portions there is the chance that one drop wire will move into the slot of an adjacent wire and support the latter even though its warp be defective. The harnessing of the warp requires that certain threads and their drop wires be raised while others are depressed. At the beat-up of the lay all of the threads are subjected to a temporary increased tension which may result in a slight upward movement of the drop wires, some of them moving farther than others. In each of these instances a condition exists which permits drop wires to become interlocked. Also, at the time of warp fault the drop wire of the defective thread will be down on the bar, but will be raised when the weaver corrects the fault, and this raising might cause interlocking.

Various attempts have been made to form drop wires of different styles of motions

either with rounded tops or with extended upper ends in order to prevent the interlocking. The drop wire must always be so proportioned that the major part of its weight lies below the surface which rests on the warp in order to retain the drop wire in upright position, and this consideration limits the height of the solid part of the drop wire above the slot. It is an important object of my present invention to place the previously mentioned lobes in such a position relatively to the contact bar that when a drop wire is in the lowest position it can occupy, that is, supported by the contact bar, the upper end thereof will be in substantial horizontal alignment with the lobe of an adjacent drop wire which may be raised. In this way I prevent a low drop wire from having an upper corner thereof pass into the slot of the adjacent drop wire.

With the objects indicated above and others which will appear as the description proceeds, my invention resides in the combination and arrangement of parts hereinafter described and set forth in the claims.

In the accompanying drawing, wherein a convenient embodiment of my invention is set forth,

Fig. 1 is a vertical central section through a warp stop motion employing my improved bar and drop wire,

Fig. 2 is an enlarged section similar to a portion of Fig. 1 showing the relation between the contact bar and two drop wires one of which is indicated raised in full lines 85 and the other down in dotted lines.

As shown in Fig. 1 a threaded supporting rod R has strung therealong a plurality of supporting and spacing units 10 the right hand one of which may be engaged by a nut 11 on the rod effective to clamp said units against an end plate 12 movement to the left of which is resisted by nut 13 on the rod. Each contact bar, designated generally at B, has an outer inclosing sheath or grounded electrode 14 having a vertical wall 15 in which is formed a longitudinally extending rib 16. The top and bottom edges of the grounded electrode are bent horizontally and then downwardly and upwardly, respectively, as 100

at 17 and 18, to define grooves between which are located the upper and lower ends of a live electrode 19. The latter has a contact surface 20 which lies within the outline of 5 the grounded electrode, that is, a line joining the right hand surface of the bent ends 17 and 18 as shown in Fig. 2 will pass to the right of the surface 20. Suitable insulating material may be provided to maintain the 10 electrodes in electrical separation.

The matter already described is substantially the same as that set forth in my aforesaid application and so far as this invention is concerned it is significant to note that the 15 top folded over edge 17 of the grounded electrode projects beyond the live surface 20, so that access to the latter by a body falling past said grounded edge 17 is afforded only by a lateral motion to the left as viewed in Fig. 2 20 on the part of the falling body.

The drop wire D forming the subject matter of my present invention has an open slot 30 in the bottom portion thereof to receive a warp thread and has a closed slot 31 25 in the upper part thereof, there being a hole 32 punched between said slots for the purpose of reducing the weight of the drop wire. The slot 31 has lower and upper portions 33 and 34, respectively, which are separated by lobes 30 or similar inwardly extending camming projections 35. The right and left hand edges of the lower part of the slot may be defined 35 by walls 36 and 37, respectively, while the corresponding walls of the upper part 34 40 may be defined by walls 38 and 39, respectively. The walls 37 and 39 are in alignment, though not necessarily so, and this relation is also true of the walls 36 and 38. It is important to note, however, that the space between the upper walls 38 and 39 is greater than the distance separating nearest parts of the right and left hand lobes 35 as designated by points 40 and 41, respectively.

In operation, the warp W will normally 45 support the drop wire so that the lobes are above the top edge of the bar, thereby keeping the surface 20 electrically separated from the grounded electrode. When a drop wire falls the lobe having point 41, for instance, 50 will engage the rib 16 to move the drop wire to the left, the corresponding point 40 of the other lobe having previously fallen to a point below the rounded edge 17 of the inclosing electrode. The right hand lobe will therefore 55 move under the upper right hand edge of the bar, and the wall 38 will approach the bar. This necessary lateral movement of the wire is possible because the upper part 34 of the slot is of sufficient width. Current may then 60 flow from the live electrode through the right hand lobe, through the drop wire, through the opposite lobe and rib 16, to the grounded electrode.

The drop wire is preferably symmetrical 65 about its vertical central axis so that it may

be threaded or strung on the bar with either the wall 36 or the wall 37 to the right, and the points 40 and 41 are preferably in horizontal alignment when the drop wire is upright. As shown herein the lobes are symmetrical about a horizontal axis passing through them, but this is not a necessary relation. 70

From an inspection of Fig. 2 it will be seen that when a drop wire, such as the one indicated in dotted lines, is in the lowest position which it can occupy because of the engagement with the detector bar, the top edge 50 thereof will lie opposite portions of the lobes 35 and the laterally offset position of the detector which might otherwise permit it to become interlocked with the adjacent drop wire shown raised in full lines, is prevented by said lobes. As the weaver ties a broken warp there is therefore no likelihood that the corresponding drop wire will become entangled with either of the drop wires adjacent thereto as it is raised. 85

From the foregoing it will be seen that I have provided a drop wire and contact bar 90 for an electrical warp stop motion so proportioned that the drop wire may have the necessary lateral movement to electrically connect the insulated electrodes of the bar. It will also be seen that the lobes which act to effect a lateral movement of one drop wire will in another drop wire occupy a higher position serving to prevent interlocking of the drop wires. 95

Having thus described my invention it will 100 be seen that changes and modifications may be made therein by those skilled in the art without departing from the spirit and scope of the invention and I do not wish to be limited to the details herein disclosed, but what I 105 claim is:

1. In an electrical warp stop motion, a contact bar, a plurality of drop wires having closed vertical slots through which the bar passes, lobes formed on each drop wire and extending into the slot thereof, the lobes of a drop wire when in highest position attainable relatively to the bar lying near the top of an adjacent drop wire in the lowest position attainable relatively to the bar to prevent the top of the second drop wire from entering the slot of the first drop wire. 110

2. In an electrical warp stop motion, a contact bar, a plurality of drop wires having vertical slots through which the bar passes, lobes formed on each drop wire and extending into the slot thereof, a longitudinally extending camming rib on the bar to engage and limit downward movement of a fallen drop wire, the lobes of a drop wire in normal position being placed to engage the top of an adjacent fallen drop wire and prevent the latter from entering the slot of the drop wire in normal position. 115

3. In an electrical warp stop motion, a 120

contact bar, drop wires having slots through which the bar extends, inwardly projecting cam portions on each of the drop wires extending into the slots, a camming rib on the bar to engage a cam portion of a fallen drop wire and move the same laterally to effect electric contact, the cam portions of a drop wire in normal raised position located to engage the top of an adjacent fallen drop wire to prevent the latter from entering the slot of the raised wire.

4. In an electrical warp stop motion, two electrodes one of which overhangs the other, a drop wire with a slot through which the electrodes extend, a pair of lobes on the drop wire extending into the slot, and means to engage one lobe as the drop wire falls to move the other lobe under the overhanging electrode and into engagement with the other electrode, that part of the slot above the lobes being wider than the distance between the lobes, whereby a lobe is capable of movement under the overhanging electrode.

In testimony whereof I have hereunto affixed my signature.

OSCAR V. PAYNE.
